[57] CLAIM

The ornamental design for a combination handset and
stand cellular telephone unit, as shown and described.

DESCRIPTION

FIG. 1 is a top plan view of a combination handset and stand cellular telephone unit showing our new design;
 FIG. 2 is a front elevational view thereof;
 FIGS. 3 and 4 are respectively left and right side elevational views thereof;
 FIG. 5 is a bottom plan view thereof;
 FIG. 6 is a rear elevational view thereof;
 FIG. 7 is a vertical sectional view thereof, taken along
 line VII—VII of FIG. 2;
 FIG. 8 is also a top plan view as in FIG. 2, with the
 display area in power-activated status;
 FIG. 9 is a top plan view of the stand and handset
 shown spaced apart; and
 FIG. 10 is a front, top and right side perspective view of
 the handset, and a right side perspective view of the
 stand, in cradled relationship.
